UNITED STATES PATENT OFFICE.

ROBERT N. ALLEN, OF METHUEN, MASSACHUSETTS, ASSIGNOR TO U. S. BOBBIN & SHUTTLE COMPANY, OF PROVIDENCE, RHODE ISLAND, A CORPORATION OF NEW JERSEY.

SHUTTLE-CUTTING MACHINE.

1,126,337.

Specification of Letters Patent.

Patented Jan. 26, 1915.

Application filed March 14, 1914. Serial No. 824,810.

To all whom it may concern:

Be it known that I, ROBERT N. ALLEN, a citizen of the United States, residing at Methuen, in the county of Essex and State 5 of Massachusetts, have invented a new and useful Improvement in Shuttle-Cutting Machines, of which the following is a specification.

This invention relates to certain new and 10 useful improvements in shuttle heading machines, and relates more particularly to a machine of the type generally indicated which is used to hollow-out shuttle heads.

The object of the invention is to provide 15 a machine of the type indicated, which more expeditiously performs the required operation, and which can be easily and quickly operated so as to increase the output.

Further, the invention aims to provide 20 means which positively holds the shuttle against movement during the cutting action of the machine, and one in which various adjustments can be easily and quickly obtained, in setting up the machine for operation 25 on a shuttle.

Still further, the invention aims to provide means which will automatically return or restore the shuttle to a position out of engagement with the cutter, upon completion 30 of the cutting action.

In the drawings Figure 1 is a front side elevation of the machine. Fig. 2 is a right side elevation thereof. Fig. 3 is a top plan view.

In proceeding in accordance with this invention, a vertically adjustable guide knee 1 is provided on which a cross slide 2 is mounted and adjustably moved by means of a hand wheel 3. A clamp screw 4 is employed to secure the cross-slide 2 to the knee 1 in its adjusted position. A post 5 slides vertically in a bearing 6 and has connected thereto a base plate 7, which has an extension 7', the extension having spaced pending ears 8 which receive therebetween a lug 9 formed on the upper end of a guide rod 10, to which ears the lug is pivoted by a pin 11. Rod 10 has a sleeve thereon which slides in a bearing 11' carried by the cross slide 2, the ends 12 and 13 of the sleeve being provided with adjustable stop collars 14 and 15 respectively, which engage the re-

spective top and bottom faces of the bearing 11. A rod 16 is pivotally connected to the lower end of guide rod 10 and may be actuated by a foot treadle 16'. A U-shaped flat spring 17 is secured at its free ends to the cross slide 2 and to the extension 7' of the base plate 7, in order to restore the base plate 7 and connected parts to normal position after same has been depressed by the rod 16 for the purpose to be later herein set forth. Rigidly secured to the base plate 7 is a head 18 of U-shape which has bearings 19 and 20 at its free upper ends. A housing 21 is mounted to align with the space between said free ends of the head 18 and has a shaft 26 journaled therein, which shaft may be suitably driven, and contained within the housing is gearing which driven from 60 the shaft 26 in turn drives the cutter 22.

A shuttle engaging disk 27 is mounted on a bushing 28 which is journaled in bearing 20 and is adjustably clamped thereto by a clamping screw 29. Extending through the 75 bushing 28 is a sliding pin 30 which is manually moved by a knurled head 31 that is connected thereto. Pivotally carried by a bushing 32 which is mounted in bearing 19 is a plate 33 of a length greater than the 80 length of the shuttle, the bushing 32 being held in adjusted position by means of a clamp screw 34. Projecting outwardly from the rear face of the plate 33 is a perforated boss 35 through which vertically slides an 85 arm 36 which arm is adjustably held in the boss by a set screw 37, the lower end of the arm 36 being formed of U-shape so as to provide a stop 38 which projects on the front face of plate 33. A similar stop 90 mechanism is provided at the opposite end of the plate 33 at 39. Similarly an end stop 40 is adjustable on a rod 43 which rod is attached to the plate 33 by a lug 44. The plate 33 is further provided with an adjustable leg 41 which at its lower end rests on a projection 42 that is in suitable rigid connection with the holder 18, the leg 41 being for the purpose of supporting and steadyng the plate 33 in horizontal position.

In operation the bottom of the shuttle is engaged by the stops 38 and 39, and one end of the shuttle is engaged by the end stop 40,

whereupon the plate 33 and the disk 27 are adjusted so as to center the shuttle or the block of wood from which the shuttle is being formed, relative to the cutter 22, to bring the front end of the cutter closely adjacent to the wall *b* of the shuttle opening *c*, the pin 30 having been previously inserted through a hole *H*, provided therefor in the block. The post 5 is then depressed until the stop collar 14 engages the upper face of the bearing 11', whereupon pressure is placed on the plate 33 and the shuttle by the hands of the operator to move the plate carrying the leg 41 downward until the leg 15 engages projection 42, which latter movement causes plate 33 and the shuttle, to move to a horizontal plane determined by adjustment of leg 41 after which the shuttle is manually raised to a vertical position 20 on the pivot pin 30 causing the cutter to act on the shuttle so as to round same at *a*, whereupon pressure is released on the treadle, which causes the spring 17 to raise the post 5 up to normal position, whereupon the pin 30 is released, and the operation 25 is completed. The cutter 22 and the contracted upper or top portion of the housing 21 are received in the usual channeled portion *c* which portion is formed in the 30 block prior to the latter being subjected to the action of the present invention, the channeled portion *c* being common to all shuttles. It will also be understood that the shuttle block is held in being operated upon, with 35 its top face or side down, so that the cutter acts beneath the block, the latter being placed in overlying relation to the cutter and above same.

Having thus described my invention, I 40 claim as new and desire to secure by Letters Patent;—

1. In a machine of the type set forth, a vertically adjustable knee, a cross slide carried by the knee, a base plate vertically movable relative to and supported by the cross slide, a U-shaped spring between the base plate and the cross slide, means to depress the base plate against the action of the spring, a head on the base plate, a disk and 45 a pin movably supported by the head to engage the shuttle, a plate also adjustably carried by the head, said plate having adjustable stops thereon to engage the bottom and an end of the shuttle, a cutter disposed 50 in the space between the plate and disk, a leg depending from the plate, and a stop to engage the leg to thereby hold the plate in horizontal position.

2. In a shuttle cutting machine, a cutter, 60 a shuttle holder arranged adjacent to the cutter, means to engage the shuttle to allow the latter to have pivotal movement thereabout, whereby the shuttle may be moved from a horizontal to a vertical position, 65 means to support the holder and shuttle en-

gaging means whereby the same may have vertical movement, and means to lower said supporting means.

3. In a shuttle cutting machine, a cutter, a pivoted shuttle holder arranged adjacent to the cutter, means to engage the shuttle to allow the latter to have pivotal movement thereabout whereby the shuttle may be moved from a horizontal to a vertical position, means to support the holder and 70 shuttle engaging means whereby the same may have vertical movement, means borne by the supporting means to limit the downward extent of pivotal movement of the holder so as to enable the holder to be held 75 in a horizontal position, and means to operate said supporting means.

4. In a shuttle cutting machine, a head, a shuttle carrier borne by said head, an adjustable pivoting device carried by the head 85 to engage the shuttle to hold same on the carrier and to also allow said shuttle to have pivotal movement about said device while the latter remains stationary, a cutter, and means to operate said head toward and 90 away from the cutter.

5. In a shuttle cutting machine, a frame, a post slidable on the frame, a U-shaped head connected to the post, a plate having bottom and an end shuttle engaging stops, 95 means to pivotally connect said plate to one side of the head, a plate having a pin thereon adjustably connected to the opposite side of the head, said pin being receivable in an aperture provided for its reception 100 in the shuttle and said plate being adapted to clamp the shuttle to the first named plate, a cutter, and means to operate said post.

6. In a shuttle machine, a frame, a post 105 slidable in the frame, a spring held base plate on the post, an extension on the base plate, means connected to said extension to depress said base plate against the action of said spring, a U-shaped head on the base 110 plate, a shuttle carrier pivoted to one side of the head, a clamping device on the other side of the head to clamp the shuttle to said carrier, means borne by the clamping device to pivotally engage the shuttle, and a cutter 115 arranged in the space between the sides of the head.

7. In a shuttle machine, a vertically movable head, a cutter, means to raise and lower the head relative to the cutter, a shuttle 120 carrier on the head, and relatively stationary means carried by the carrier to pivotally support the shuttle to allow the latter to be turned from a horizontal to a vertical position after lowering of the head and there- 125 with the carrier.

8. In a machine for operating on shuttles having openings, a carrier for the shuttle, a cutter receivable in the opening, means to relatively move the cutter and carrier to 130

cause the cutter to enter the shuttle opening and relatively stationary means whereby the shuttle may be moved about said last named means to a vertical position on the carrier to enable the cutter to round one of the end walls which the shuttle opening provides.

In testimony whereof I have signed my name to this specification in the presence of two subscribing witnesses.

ROBERT N. ALLEN.
